UNITED STATES PATENT OFFICE.

ISIDORE BIRGÉ, OF PHILADELPHIA, PENNSYLVANIA, ASSIGNOR TO THE TRANSIT APPARATUS COMPANY, (LIMITED,) OF SAME PLACE.

STORE-SERVICE APPARATUS.

SPECIFICATION forming part of Letters Patent No. 325,384, dated September 1, 1885.

Application filed April 23, 1885. (No model.)

To all whom it may concern:

Be it known that I, ISIDORE BIRGÉ, a citizen of the United States, residing in the city and county of Philadelphia, in the State of Pennsylvania, have invented an Improvement in Store-Service Apparatus, of which the following is a specification.

My invention relates in general to the class of store-service apparatus in which the traveling carrier is a basket or other goods-receiver suspended from the depending arm or hanger of a one or two wheeled truck, the wheel or wheels of which travel upon an elevated track composed of a single rail.

My invention relates specifically to the carrier receivers or devices for receiving the carriers at the end of a given line of track and for permitting of the descent or bringing down of said carriers, one by one, from the level of the track to a lower level and within the reach of an attendant, and it comprehends improvements not only upon the receivers themselves, but also upon certain devices for stopping or arresting the carriers at the end of a given track and before their travel upon the receiver.

25 In Letters Patent of the United States No. 291,280, granted January 1, 1884, upon my application, there is shown and described a carrier-receiving apparatus of substantially the character herein set forth and improved upon; and in Letters Patent of the United States, No. 300,198, granted June 10, 1884, upon my application, there is likewise shown and described a stop apparatus for, under certain 30 conditions of disposition of parts, arresting the movement of a carrier onto a receiver of substantially the character herein employed and improved upon.

35 My present invention comprehends means for occasioning the conjoint operation of the carrier-receiving apparatus and the carrier-arresting device, so that they automatically co-operate in the receiving and discharge of a given carrier and in the arrest of a succeeding carrier until the time comes for its discharge; and it further comprehends specific 45 improvements both in the construction and arrangement of the receiver and in the application and control of its operating-cord.

50 Apparatus conveniently embodying a good

form of my improvements is represented in the accompanying drawings and described in this specification, the particular subject-matter claimed as novel being hereinafter definitely specified.

55 In the accompanying drawings, Figure 1 is a side elevational side of a carrier-receiver conveniently embodying my improvements, the parts being in the position which they occupy when the receiver has been elevated and has received a carrier, and when the rear arm of the arrester has been deflected to arrest upon the track a succeeding carrier, that side of the hood which is nearest the eye being, for clearness of representation, omitted. Fig. 2 is a view similar to that of Fig. 1 of the same device, in the position, however, which the parts assume when the receiver has been dropped, and when the carrier, which it is represented in Fig. 1 as containing, is being brought down 60 upon the lifting-cord. In this view the carrier shown in Fig. 1 as being arrested by the rear arm of the arrester is shown as arrested by the front arm of said arrester. Fig. 3 is a view in perspective of the carrier-receiver in 65 its elevated position, sight being taken from the opposite side from that represented in Figs. 1 and 2; and Fig. 4 is a view in perspective of the hood shown detached.

70 Similar letters of reference indicate corresponding parts.

75 In the drawings, A represents the terminal portion of a track or carrying rail, which, in the mounting of the apparatus represented, is sustained by a depending forked suspender, B. Parallel with the track and likewise supported by the suspender B, is a guard-rail, A^X, between which and the track the hanger of the carrier depends and travels.

80 C C represent a type of one-wheeled traveling carriers, several of which are represented, with which the apparatus depicted is proportioned to operate.

85 D is a standard secured to the track (or other fixture) at a suitable distance from the extremity thereof, to which is pivoted what I term the "carrier-arrester" E, which is, in effect, a lever of substantially the character of the pivoted stop-bar described in my Letters Patent No. 300,198, and the two arms of which, 90

which I respectively designate as the "front" arm, e , and the "back" arm, e' , are of such conformation as to present on each side of their common fulcrum one or more segmental or 5 are shaped faces or seats, so to speak, which preferably correspond in curvature with the curvature of the periphery of a carrier-wheel, and against which the exterior rim of said wheel is adapted, when the arrester is in given 10 positions, to abut.

The carrier-receiver is essentially composed of what I term a "track" or "floor" bar, a guard or cover bar, and cross-bars, or other devices for connecting the said track and cover 15 bars together.

F is what I term the "track-bar," which is conveniently pivoted to the extremity of the track, constitutes, when in its elevated position, a continuous connection of said track, 20 and is, in effect, the floor of the receiver. A breast and parallel with but a certain distance from the track-bar is a guard-bar, F' , which is pivoted to the extremity of the guard-rail, and which serves as a guard for the carrier-hanger as the carrier runs on the track-bar of the receiver. The pivoted track-bar F carries or is provided with a cover-bar, G , being a parallel bar, preferably of greater 25 length than the track-bar F , and connected therewith, as well as with the guard-bar F' , by cross-bars, or any preferred connecting device—such, for instance, as the twin bulging spiders H H' . The length which the cover-bar is represented as having in excess of the 30 length of the pivoted track-bar forms what I term a "bell-muzzle," g , the same being a flaring throat, the office of which, when the receiver is elevated, is to guide the carrier onto the track-bar, and when the receiver as an entirety has assumed its depending or vertical 35 position, to insure the deposit, in said depending receiver, of the wheel of a carrier which may have escaped the arrester as the latter, together with the receiver, was in the act of dropping, whereof hereinafter. It will now 40 be understood that the receiver is itself a cage practically inclosed at sides and top, and the floor of which, when in the horizontal position, is essentially constituted by the track-bar F or continuation of the track; and that 45 when in a vertical position said receiver is in effect a suspended pocket or cage, from which a carrier cannot escape except at the will of the operator, as hereinafter explained.

I is a link or rod for connecting the carrier-arrester and the carrier-receiver so that they operate together. The connection is conveniently effected by providing the outer extremity of the cover-bar G of the carrier-receiver 50 with a link-bar, g' , provided with an eye, g , through which the outer extremity of the link I , which is pivotally connected with the front arm of the arrester, passes. It is obvious that the lift of the carrier-receiver from the position which it is represented as occupying in 55 Fig. 2 to that which it is represented as occu-

pying in Figs. 1 and 3, will occasion such a corresponding movement of the carrier-arrester as will cause it to assume the position represented in Fig. 1, and that the drop of the receiver will occasion an opposite movement of the arrester. The lower or outer extremity of the track-bar F is provided with a pivoted detent, f , which at a point beyond its fulcrum, and conveniently at a heel, f' , is connected 70 with the lifting-cord J ; which passes up and over a pulley near the ceiling, and through a pull upon which the carrier-receiver is moved from the position represented in Fig. 2 to that represented in Fig. 1. When tension is exerted upon the cord so as to raise the receiver, the pivoted detent f is deflected so as to seat itself in a notch, f' , formed to receive it in the carrying-face of the track-bar F , in which position the detent becomes a continuous connection of the track. In the depending position of the receiver the detent falls out of its notch and blocks the discharge-opening of the receiver, as shown in Fig. 2.

K is a housing upon the cover-bar of the receiver, which contains two pulleys, k k' , between which the lifting-cord J passes and which tend to ease its movement with respect to the outer end of the cover bar G , with respect to which the cord of course must have a 95 fixed passage.

L is a hood, applied conveniently by being connected to the forked suspender B , and conveniently formed of two webs of wire-work. It extends beyond the extremity of the track-bar and so as to form an incasing contrivance, so to speak, for the receiver. The particular object of the hood, however, is to prevent possible tangling of the cord with parts of the receiver when sudden and jerky traction is exerted upon it.

In the foregoing description of construction of apparatus it is believed that the operation has been sufficiently indicated. It is, however, proper to add that the normal position of the parts is that represented in Fig. 2, in which case the receiver is vertical and depending and the front arm of the arrester deflected so as to block the track, in which position a carrier traveling down the track to its terminus encounters the front arm of said arrester and is brought to a standstill. When, then, it is desired to bring down the arrested carrier, traction is exerted upon the cord of the receiver and the latter is elevated from its vertical to its horizontal position, or that represented in Figs. 1 and 3. In the said act of elevating the receiver the front arm of the arrester is also elevated and the rear arm depressed, so that as soon as the receiver is horizontal the arrested carrier escapes from the arrester and gravitates upon the track-bar of the receiver over the pivoted detent, which in the then elevated position of parts is a continuous connection of the said track-bar, and out to and 120 against the heel of the detent and the cord.

In the above action of lifting the receiver

as the front arm of the arrester lifts to permit the onward travel of the arrested carrier, the rear arm, as stated, drops so as to constitute a guard against the passage of a succeeding carrier, should one at the time arrive at the terminal. When the carrier first considered is within the receiver, the cord is slackened, the receiver drops, and the carrier descends upon the bight formed in the cord, after the manner set forth in my Patent No. 291,280, hereinbefore referred to. As the carrier drops upon the cord, the detent, as the cord under the weight of the carrier becomes taut, is lifted from out its notch and blocks the discharging-throat, so to speak, of said receiver, so that in the event of the accidental passage of two carriers past the arrester into the receiver at the same time, the second carrier, even in the vertical position of the receiver, is arrested and prevented from descending with the first carrier upon the cord. The act of slackening the cord and permitting the drop of the receiver occasions the retilting of the arrester, so that its rear arm lifts as its front arm drops, and thereby permits the escape from the rear arm of any carrier which may happen to have been arrested by said rear arm at the time when it was down, and the limited advance of said carrier against the depressed frontarm. If desired, the housing which carries the cord-pulleys may be pivoted so as to prevent any possibility of the cord binding between the pulleys.

Such being a description of a good construction of my device, it is obvious that the essential features of the invention are, the positive connection of the receiver with the arrester, so that the said devices co-operate or mutually contribute to the regulated receiving and discharge of the carriers one by one at the terminus; the construction of the receiver itself as a closed cage; the provision of the detent or additional arrester, so to speak, within the receiver, to prevent the accidental dropping of a carrier; the application of the hood to prevent the entanglement of the cord, and the provision of the pulleys or a kindred anti-friction contrivance for easing the play, while safely retaining the position, of the cord with respect to the receiver.

Having thus described my invention, I claim—

1. In a store-service apparatus, in combination with a track which is suitably suspended or supported, an arresting device adjacent to the terminal extremity of the track, a receiving device applied to the extremity of the track and adapted to have movement with respect thereto, and a connecting device between said receiving and said arresting device which occasions their conjoint operation, as and for the purposes set forth.

2. In a store-service apparatus, the following elements in combination: a track, an arresting device adjacent to the extremity of said track, a receiving device applied to the extremity of said track, a connecting device for

connecting the arresting device with the receiving device, and a cord for operating said receiving device, substantially as set forth.

3. In a store-service apparatus, in combination with a track suitably supported or suspended, a carrier-receiver applied to the terminal extremity of said track, a pivoted detent or kindred arresting device applied to said carrier-receiver, and a cord connected with said detent for operating said receiver, substantially as set forth. 70

4. In a store-service apparatus, in combination with a track suitably supported or suspended, a carrier-receiver applied to the terminal extremity of said track, a cord connected with said receiver, and pulleys applied to said receiver for easing the play of the cord, substantially as set forth. 80

5. In a store-service apparatus, the combination of a track, a pivoted carrier-receiver applied to the terminal extremity of the track, a cord for operating said pivoted receiver, and a hood for preventing entanglement of the cord, substantially as set forth. 85

6. In a store-service apparatus, in combination with a track suitably suspended or supported, a pivoted carrier-arrester having an arresting-arm upon each side of its pivot, a pivoted cage-like carrier-receiver composed, 95 essentially, of a track-bar and a cover suitably connected, bars, a link or rod connecting the pivoted arrester with the pivoted receiver, and a cord for elevating the receiver, substantially as set forth. 90

7. In a store-service apparatus, in combination with a track suitably suspended or supported, a pivoted carrier arrester, a pivoted carrier-receiver, a link or rod connecting the pivoted arrester with the pivoted receiver, a pivoted detent applied to said receiver, and a cord connected with said detent and adapted to control the throat or carrier-escape opening of said receiver, as and for the purposes set forth. 105

8. In a store-service apparatus, the combination of a track, a carrier-receiver applied to said track, being essentially a closed guard or cage for a carrier, and provided with a track-bar which, when the receiver is elevated, is a continuous connection of the track, a pivoted detent applied to the track-bar of the receiver which, when the receiver is elevated, forms a continuous connection of the track-bar, and a cord for conjointly operating both the detent 115 and the carrier-receiver, substantially as described. 110

9. As an article of manufacture, a carrier-receiver for a store-service apparatus of the class herein recited, provided with a track-bar, being a continuation of the main track, and a pivoted detent being a continuation of the track-bar, substantially as described. 125

10. In combination with the pivoted carrier-receiver provided with the lifting-cord, pulleys for fixing one point of bearing or connection and for easing the movement of the cord 130

with respect to the receiver, substantially as set forth.

11. In combination with the pivoted arrester, the pivoted receiver, the pivoted detent, and the cord for operating both the detent and the receiver, substantially as described.

12. As an article of manufacture, a carrier receiver provided with a bell-muzzle or flaring throat, as and for the purposes set forth.

10 13. As an article of manufacture, a carrier receiver for a store-service apparatus of the class herein recited, consisting of an inclosed

cage adapted to be pivoted to the terminal extremity of the track, and provided as to its lower opening or floor region with a track-bar ¹⁵ or a continuation of the track, substantially as set forth.

In testimony whereof I have hereunto signed my name this 28 day of March, A. D. 1885.

ISIDORE BIRGÉ.

In presence of—

J. BONSALL TAYLOR,
WM. C. STRAWBRIDGE.

Correction in Letters Patent No. 325,384.

It is hereby certified that in Letters Patent No. 325,384, granted September 1, 1885, upon the application of Isidore Birgé, of Philadelphia, Pennsylvania, for an improvement in "Store-Service Apparatus," an error appears in the printed specification requiring the following correction: In line 57, page 1, the word "side" after "elevational" should be stricken out and the word *view* inserted instead; and that the said Letters Patent should be read with this correction therein that the same may conform to the record of the case in the Patent Office.

Signed, countersigned, and sealed this 15th day of September, A. D. 1885.

[SEAL.]

G. A. JENKS,
Acting Secretary of the Interior.

Countersigned:

M. V. MONTGOMERY,
Commissioner of Patents.
